UNITED STATES PATENT OFFICE.

GEORGE J. A. MOLIQUE, OF GRANITE CITY, ILLINOIS.

CLOTHESLINE HOLDER.

Application filed August 18, 1927. Serial No. 213,886.

This invention relates to clothes line holders and is designed as an improvement over the holder shown in my Patent #1,632,616 issued June 14, 1927.

- 5 A primary object of the invention is to provide a holder of this character the automatic clamping member of which is mounted for sliding movement in the housing forming a part of the clamp, said member 10 being equipped with means to take the wear of the sliding movement without danger of shearing of any of the parts during such movement such as is liable to occur in the patented structure.
- 15 Another object is to so construct the clamping member of the holder that a reliable guide will be formed for the rope without necessitating curving of the teeth of the clamp.
- 20 In carrying out these objects, the invention is susceptible of modification without departing from the spirit or sacrificing any of the advantages of the claimed invention; there being shown in the drawings for illustrative purposes the preferred and practical form, in which:

Figure 1 represents a side elevation of a clothes line secured in position by this improved holder;

30 Fig. 2 is a side elevation of the clamp detached;

Fig. 3 is a perspective view taken from the side opposite to that from which Fig. 2 is taken; and

35 Fig. 4 is a vertical section taken on the line 4—4 of Fig. 2.

In the embodiment illustrated a post P is shown and a fixed structure in the form of a wall W between which the rope R is stretched and to which it is secured. One end of the rope is fixed to the post P and the other end is clamped to the wall W by the holder 10 constituting this invention.

The holder 10 includes a housing similar to that shown in the patent above referred to and which has attaching flanges 11 and 12 at one end for fixing it to the wall W. One side wall of this housing has an obliquely arranged slot 13 in which the clamping member in the form of a bar 15 is adapted to slide. This bar 15 is substantially L-shaped with longitudinally spaced rivets 16 extended through the long arm or body portion of the bar. A combined guide and wear plate 17 is arranged on the outer face of the housing between it and the rivet heads and

through which the rivets pass. This plate has a trough or groove 18 extending longitudinally thereof and which fits in the slot 13 bearing against the adjacent face of the 60 bar 15 and which operates to take the wear from the side walls of the slot and thereby prevent shearing off of the rivets.

The short arm 19 of the bar has a groove 20 extending around its outer edge and 65 curved as shown in Fig. 2 to form a guide for the rope R in its passage around the clamp.

The outer edge of the long arm of the bar has a plurality of teeth 21 arranged in 70 spaced relation with the top of the housing between which and said teeth the rope is designed to be clamped.

In the use of this holder the rope R is secured at one end to the post P and the 75 other end is inserted in the holder being passed around the grooved end of the bar and threaded between the teeth 21 and the top of the housing. A pull on the rope when the clothes are hung thereon will tend 80 to pull the sliding clamp 15 outwardly and cause the teeth 21 to bite into the rope during its compression between the inner face of the housing top and the teeth.

It will thus be seen that the grooved portion of the wear plate in its movement in the slot 13 will relieve the rivets from all wear and thus greatly prolong the life of the holder, and the use of straight teeth instead of curved ones as shown in the patent will 90 also cheapen the construction of the holder while producing the same result.

Without further description it is thought that the features and advantages of the invention will be readily apparent to those 95 skilled in the art, and it will of course be understood that changes in the form, proportion and minor details of construction may be resorted to, without departing from the spirit of the invention or its scope as 100 claimed.

I claim:

1. A device of the class described comprising a housing having a top and a side wall with a slot in said side wall at an angle 105 to the horizontal, a clamping member mounted to slide in said housing and adapted to cooperate with a wall of the housing to clamp a rope between them, and a combined wear plate and guide mounted in said 110 slot and carried by said member.

2. A device of the class described com-

prising a housing having a top and a side wall with a slot in said side wall at an angle to the horizontal, a clamping member mounted to slide in said housing and adapted to cooperate with a wall of the housing to clamp a rope between them, a combined wear plate and guide mounted on the outer face of said housing and having a grooved portion extending into and through the slot and secured to said clamping member whereby the wear incident to the sliding of said member is taken by said plate.

3. A device of the class described comprising a housing having a top and a side wall with a slot in said side wall at an angle to the horizontal, a clamping member mounted to slide in said housing and adapted to cooperate with a wall of the housing to clamp a rope between them, one end of said clamp being grooved to receive a rope and its upper edge having transversely straight teeth to facilitate gripping of a rope thereby.

GEO. J. A. MOLIQUE.
